(57) **CLAIM**

The ornamental design for a fin for surcraft, as shown and described.

DESCRIPTION

FIG. 1 is a top view of a fin for surcraft showing my design, wherein the fin for surcraft illustrated is a left fin for surcraft;

FIG. 2 is a front view of the left fin for surcraft of FIG. 1; FIG. 3 is a rear view of the left fin for surcraft of FIG. 1; FIG. 4 is a left side view of the left fin for surcraft of FIG. 1;

FIG. 5 is a bottom view of the left fin for surcraft of FIG. 1;

FIG. 6 is a right side view of the left fin for surcraft of FIG. 1;

FIG. 7 is a left perspective view of the left fin for surcraft of FIG. 1;

FIG. 8 is a right perspective view of the left fin for surcraft of FIG. 1;

FIG. 9 is a top view of a second embodiment of a fin for surcraft having a mirror image of the fin for surcraft of FIG. 1, wherein the fin for surcraft illustrated is a right fin for surcraft;

FIG. 10 is a front view of the right fin for surcraft of FIG. 9;

FIG. 11 is a rear view of the right fin for surcraft of FIG. 9; FIG. 12 is a left side view of the right fin for surcraft of FIG. 9;

FIG. 13 is a right side view of the right fin for surcraft of FIG. 9; and,

FIG. 14 is a bottom view of the right fin for surcraft of FIG. 9.
